UNITED STATES PATENT OFFICE.

HARRY W. SHEEHY, OF AKRON, OHIO.

CAN-OPENER.

986,319.

Specification of Letters Patent.

Patented Mar. 7, 1911.

Application filed June 14, 1910. Serial No. 566,880.

To all whom it may concern:

Be it known that I, HARRY W. SHEEHY, citizen of the United States, residing at Akron, in the county of Summit and State 5 of Ohio, have invented certain new and useful Improvements in Can-Openers, of which the following is a specification.

This invention comprehends certain new and useful improvements in can opening devices, and the invention has for its primary object a simple, durable and efficient construction of a tool of this character which may be easily applied to and adjusted for cans of different sizes and easily manipulated to make a clean cut around the body portion of the can, and without danger of cutting the operator's hand.

With this and other objects as will more fully appear as the description proceeds the 20 invention consists essentially in a can opener comprising a handled shank, the handle being adjustably connected to the shank and carrying a cutter, and the shank also carrying one or more cutters, the adjustable connection between the shank and handle permitting the cutters to be brought nearer to and farther away from each other according to the size of the can, and the cutters being mounted to rotate whereby, when the device 25 is applied to the top of the can, the same can be cut off with a clean incision by turning the device around the body portion of the receptacle.

The invention also consists in certain constructions, arrangements and combinations of the parts that I shall hereinafter fully describe and claim.

For a full understanding of the invention reference is to be had to the following description and accompanying drawing, in which:—

Figure 1 is a side elevation of my improved can opener. Fig. 2 is a sectional view thereof with parts in edge elevation, 45 and Fig. 3 illustrates the main parts in perspective, detached from each other.

Corresponding and like parts are referred to in the following description and indicated in all the views of the accompanying drawing, 50 being by the same reference characters.

Referring to the drawing the numeral 1 designates the shank of my improved can opening tool, said shank being preferably in the form of a flat metal bar provided with 55 screw-threads on its opposite side-edges, as indicated at 2, the threads preferably ex-

tending only a portion of the length of the shank.

3 designates the handle of the device, said handle being preferably of cast metal and 60 preferably corrugated so as to provide a gripping surface, the handle being formed with a longitudinal bore that is threaded for a portion of its length as indicated at 4, the threaded end of the shank 1 engaging the 65 screw-threads 4 of the handle, so as to produce a longitudinally adjustable connection between the handle and shank.

The handle 3 is formed at one end with an annular groove 5 which is engaged by a 70 lip 6 which is formed on a collar 7, said collar being formed with an opening by which it is mounted to slide on the shank 1. The collar 7 is also formed with a recess 8 which accommodates a rotary cutter 9, the 75 cutter being journaled in the recess on a pivot stud or screw 10, which is preferably entered in a transverse opening intersecting the recess 8, being inserted through an aperture 11 so that the head of the pivot stud or 80 screw, will be countersunk in the interior of the collar. The end of the stud is preferably upset or riveted, as clearly illustrated in the drawing, so as to hold it in place after it has once been inserted through the cutter. 85

The shank 1 is formed at its outer end with a laterally extending head portion 1^a, said head carrying one or more rotary cutters 12 which lie in the same plane as the cutter 9. In the present instance, two of 90 the cutters 12 are employed, the same being journaled upon pivot studs 12^a that are secured to the opposite corners of the head 1^a. Preferably the studs 12^a are formed with reduced ends on which the cutters 12 are 95 journaled, so as to provide for the free movement of the cutters and prevent any binding action. If desired, the shank 1 may be formed between the cutters with an opening 1^b, by which the tool may be hung 100 up on a nail or other support when not desired for use.

From the foregoing description in connection with the accompanying drawing, the operation of my improved can opener 105 will be apparent.

In the practical use of the device the tool is applied to the top of a can and the handle 3 screwed up so as to effect the engagement of the cutters 9 and 12 with the body portion of the can preferably below the top of the same. The tool is then given a turn 110

around the body of the can, the handle being screwed, however, if found necessary in order to tightly bind the cutters against the body portion of the can and cause them 5 to make an incision. By this means a clean cut will be formed and the top of the can easily be removed with very little trouble.

Obviously, the adjustable connection between the handle and shank, not only provides means whereby the opener may be used 10 with cams of different diameters, but also enables the operator to bind the cutter as tightly as may be found necessary against the side of the can so as to cut into the tin 15 as above described.

Having thus described the invention what is claimed as new is:—

1. The herein described can opener, comprising a threaded shank, a cutter carried 20 by the shank, an interiorly threaded handle engaging the screw threads of the shank and formed at one end with an exterior annular groove, a collar mounted for a longitudinal movement on the shank and formed 25 with a lip engaging in the groove of the handle, whereby a turning movement of the handle will slide the collar along the shank and at the same time move the handle itself along the shank, and a cutter carried by the 30 collar.

2. The herein described can opener, embodying a flat shank, a cutter carried by said shank, the shank being formed on its side edges with screw threads, a collar formed 35 with a smooth opening on which it is mounted to slide freely on the shank and is held from turning thereon, a cutter carried by the collar, and an interiorly threaded handle receiving the shank and engaging the 40 threads thereof, whereby a turning move-

ment of the handle will move both handle and collar along the shank, the collar being formed with a lip and the handle with a groove received in said lip.

3. A can opener, comprising a shank 45 formed on its side edges with screw threads, an interiorly threaded handle engaging the screw threads of the shank and thereby mounted for longitudinal adjustment on the shank, the handle being formed with an annular groove, a collar mounted for longitudinal movement on the shank and formed with a lip engaging in said groove, the collar being also provided with a recess, a cutter journaled in said recess, and a cutter carried 50 55 by the shank.

4. A can opener, comprising a threaded shank, an interiorly threaded handle engaging the threads of the shank and formed with an exterior annular groove, a collar 60 mounted to move on said shank and formed with a lip engaging the groove, whereby a turning movement of the handle will effect a longitudinal movement of the handle, a collar on the shank, the collar being formed 65 with a recess, a cutter mounted in said recess, the collar being formed with an aperture extending thereacross and intersecting the recess, and a stud adapted to slip through the aperture across the recess and through 70 the cutter received in said recess, whereby to journal the cutter, the stud being engaged at one end by the shank, whereby to assist in holding the stud in place.

In testimony whereof, I affix my signature 75 in presence of two witnesses.

HARRY W. SHEEHY. [L. S.]
